US0D1098175S

(12) **United States Design Patent** (10) **Patent No.:** **US D1,098,175 S**
(45) **Date of Patent:** **** Oct. 14, 2025**

(54) **DISPLAY SCREEN WITH GRAPHICAL USER INTERFACE OR PORTION THEREOF**

(71) Applicant: **Google LLC**, Mountain View, CA (US)

(72) Inventors: **Paul Merrell**, Redwood City, CA (US);
Aaron Michael Donsbach, Seattle, WA (US); **Vinay Damodar Shet**, Millbrae, CA (US); **Jonathan Siegel**, San Francisco, CA (US); **Julien Zachary Reneau-Wedeen**, Chicago, IL (US); **Andrew Kisielius Veritas**, San Francisco, CA (US); **Daniel Caleb Gordon**, Marietta, GA (US); **Su Chuin Leong**, Oakland, CA (US)

(73) Assignee: **GOOGLE LLC**, Mountain View, CA (US)

(**) Term: **15 Years**

(21) Appl. No.: **29/913,538**

(22) Filed: **Oct. 4, 2023**

CLAIM

The ornamental design for a display screen with graphical user interface or portion thereof, as shown and described.

DESCRIPTION

The related U.S. application ser. No. 29/488,683, filed Apr. 22, 2014, now U.S. U.S. Pat. No. D 781,317, issued Mar. 14, 2017, and to U.S. application ser. No. 29/488,695, filed Apr. 22, 2014, now U.S. Pat. No. D781,318, filed Mar. 14, 2017, the disclosures of all of which are incorporated herein by reference.

The FIGURE is a front view of an image of a graphical user interface object for a display screen or a portion thereof, according to our design.

The broken lines show portions of a display screen with graphical user interface or portion thereof and form no part of the claimed design. The perimeters of the graphical user interface or portion thereof and the underlying display screen are understood to be flush.
